2 SHEETS—SHEET 2.

UNITED STATES PATENT OFFICE.

FREDERIC W. SLACK, OF CLEVELAND, OHIO, ASSIGNOR TO THE PEERLESS MOTOR CAR COMPANY, OF CLEVELAND, OHIO, A CORPORATION OF OHIO.

INTERNAL-COMBUSTION ENGINE.

1,368,661.

Specification of Letters Patent. Patented Feb. 15, 1921.

Application filed April 15, 1918. Serial No. 228,519.

To all whom it may concern:

Be it known that I, FREDERIC W. SLACK, a citizen of the United States, residing at Cleveland, in the county of Cuyahoga and 5 State of Ohio, have invented a certain new and useful Improvement in Internal-Combustion Engines, of which the following is a full, clear, and exact description.

This invention relates to internal combustion engines and has particular reference to engines of the V-type, although not necessarily confined to that type.

More specifically, the invention relates to a combined distributor drive, oil pump, and 15 supporting bracket for throttle and spark control members, one of the objects of the invention being to simplify and enhance the compactness of the engine.

A further object is to provide a distributor driving mechanism which includes a pair 20 of gears to transmit power from one drive shaft to another displaced therefrom so as to permit the distributor to be centrally located between the cylinders of a V-engine, 25 and to utilize these gears and the incasing parts therefor for oil pumping purposes.

A still further object is to form the incasing and supporting parts for the combined distributor drive and oil pump so as 30 to constitute a support for the spark control and throttle shifting members.

The invention may be briefly summarized as consisting in certain novel details of construction and combinations and arrangements of parts which will be described in 35 the specification and set forth in the appended claims.

In the accompanying sheet of drawings, Figure 1 is a side view of the rear portion 40 of an internal combustion engine of the V-type, showing conventionally by dotted lines part of the oiling system, this view representing an engine of a motor vehicle with usual throttle and spark controlling members; Fig. 2 is a view partly in elevation and partly in vertical section taken substantially along the line 2—2 of Fig. 1, looking in the direction indicated by the arrows; and Fig. 3 is a sectional plan view of the 50 distributor drive and oil pump, the section being taken substantially along the line 3—3

of Fig. 2 looking in the direction indicated by the arrows, parts being broken away.

Referring now to the drawings, 10 represents the rear part of the crank casing of an 55 engine, such as used on motor vehicles, and 11 represents two of the cylinders, the engine here shown being preferably of the V-type. In Fig. 1, 12 represents the center line of the steering column through which 60 extends the usual throttle and spark controlling posts or shafts which shift respectively the throttle controlling rod 13 and the spark controlling rod 14. The precise construction and manner in which these 65 parts are operated form no part of the present invention, and need not be further described or illustrated.

In Fig. 2, 15 represents the cam shaft of the engine, which in a V-type engine is above 70 the crank shaft between the two rows of cylinders. This shaft has a gear 16 which rotates a second gear 17 on a vertical shaft 18, this shaft 18 being utilized in accordance with the present invention to drive the combined pump and distributor driving gears. The lower part of this shaft usually extends 75 downward to the lower part of the engine to drive an auxiliary part which forms no part of this invention.

In an engine of the V-type whose cylinders are at fairly acute angle, such as 60°, in order that the distributor may be accommodated in the space between the cylinders, the distributor is desirably displaced from 85 the shaft 18 toward or directly above the driving shaft 15, and for that reason the shaft 18 instead of being carried directly up to the distributor is provided a short distance above the gears 16, 17, with a gear 19 90 which meshes with a similar gear 20 secured to a vertical shaft 21 which is coupled to the rotary member of the distributor of the ignition system, the distributor being shown at 22.

The utilization of the two shafts 18 and 95 21 displaced with respect to each other and connected by gears enables me to use these gears and inclosing parts for other purposes than the mere driving of the distributor, 100 namely, as an oil pump and for an additional purpose to be described. To this end

the gears 19, 20 are made in the form of spur gears suitable for use as a gear oil pump, and I inclose these gears in a casing composed of a lower part or body portion 5 22, which is suitably mounted and secured to a part 23 of the engine casing, and of an upper part or cap 24. The top part 24 of the casing has an upward extension 25 which incloses the shaft 21 and the coupling to the 10 rotary member of the distributor, and constitutes a support for the distributor.

At the upper part or cap 24 of the casing is the oil inlet 26 and the oil outlet 27 which are connected to the oiling system, a part 15 of which I have indicated in Fig. 1 by the dotted lines to which arrows have been applied to show the course of oil circulation. The precise details of the oiling system, the arrangement of piping, etc., is immaterial 20 to my invention, and to avoid confusion only a part of the oiling system is shown, and that in a conventional manner.

In addition to utilizing the parts as an oil pump and distributor drive, the structure of 25 which the cap or casing member 24 is a part is utilized not only to support the distributor as previously explained, but also as a supporting bracket for the throttle and spark control shafts and levers. To this end 30 the cap 24 is provided with an arm 28 with a bearing boss 29 and the upstanding part 25 of the cap is provided with a bearing boss 30 in which is journaled a shaft 31 carrying a surrounding sleeve or hollow shaft 32. The 35 former, *i. e.*, the shaft 31 is provided with a lever 33 to which the throttle controlling rod 14 previously mentioned is connected. At the inner end of shaft 31 is an arm 34 against which is pressed by a spring 35 a lever 36 which is also on the shaft 31, but loose thereon, this lever 36 having a connection with the throttle and also being designed to be turned independently of the shaft 31 by the foot accelerator. The sleeve 32 carries 40 at its outer end a lever 37 to which is connected the spark controlling rod 14 and it is provided at its inner end with an arm 38 which is connected to the adjustable part of the distributor designed to be turned to advance or retard the spark. However, the 45 precise details of the throttle and spark controlling mechanism as here shown are not essential to my invention.

It will thus be seen that the feature of 50 compactness is obtained with one structure serving the three-fold purpose of a distributor drive, an oil pump, and supporting bracket for throttle and spark control members.

60 As previously stated, my invention while having special utility in a V-type engine, may in whole or in part be used to advantage on other types of engines, such as engines having the cylinders in a single row. 65 Furthermore, I wish it to be understood that

the details of construction and arrangement may be modified considerably without constituting a departure from the spirit and scope of my invention in its broad aspects.

Having described my invention, I claim: 70

1. In an internal combustion engine having an oil circulating system and a distributor for ignition purposes, a pair of distributor drive shafts, and a pair of gears connecting said shafts; said gears being utilized 75 for oil distributing purposes.

2. In an internal combustion engine having an oil circulating system and a distributor for ignition purposes, a pair of distributor drive shafts off-set from each other, 80 gears connecting said shafts, and a casing inclosing the gears and forming with the latter an oil pump.

3. In an internal combustion engine having an oil circulating system and a distributor for ignition purposes, a pair of distributor drive shafts off-set from each other and one geared to an appropriate part of the engine so as to be driven, and the other connected to the distributor, a pair of gears connecting said shafts, and an inclosure for the 90 gears forming with the latter an oil pump.

4. In an internal combustion engine having an oil circulating system and a distributor for ignition purposes, a pair of off-set 95 vertically disposed distributor drive shafts, a horizontal shaft geared to one of said shafts for driving purposes, and the other of said off-set shafts being connected to the distributor, a pair of spur gears connecting 100 said off-set shafts, and a casing inclosing said gears and forming therewith an oil pump.

5. In an internal combustion engine having an oil circulating system and an ignition 105 system including a distributor, a combined oil pump and distributor drive mechanism including engaging gears with an inclosing casing, and spark and throttle control members supported by said casing.

6. In an internal combustion engine having an oil circulating system and an ignition system including a distributor, a combined oil pump and distributor drive mechanism, and throttle control members supported by 115 the latter.

7. In an internal combustion engine having an oil circulating system and an ignition system including a distributor, a horizontal engine driven shaft, a vertical shaft geared thereto, a second vertical shaft displaced from the first named vertical shaft and connected to the distributor, gearing connecting said two vertical shafts, and an inclosure 120 for said gearing forming with the latter an oil pump having inlet and outlet openings connected to the oil circulating system.

8. In an internal combustion engine having an oil circulating system and an ignition system including a distributor; a horizontal 125

engine driven shaft, a vertical shaft geared thereto, a second vertical shaft displaced from the first named vertical shaft and connected to the distributor, gearing connecting said two vertical shafts, and an inclosure for said gearing forming with the latter an oil pump having inlet and outlet openings connected to the oil circulating system, spark and throttle control members, said inclosure forming a support for the distributor and for said members.

In testimony whereof I hereunto affix my signature.

FREDERIC W. SLACK.
